[57] CLAIM

The ornamental design of a boat and trailer protector set, as shown and described.

DESCRIPTION

FIG. 1 is a perspective view of a boat and trailer protector set showing my new design;

FIG. 2 is a front elevational view thereof;

FIG. 3 is a side elevational view thereof;

FIG. 4 is an opposite side elevational view thereof; and, FIG. 5 is a top plan view thereof.

The broken lines shown in FIGS. 1-5 are for illustrative purposes only and form no part of the claimed design.
